UNITED STATES PATENT OFFICE.

CHARLES W. JONES, OF PHILADELPHIA, PENNSYLVANIA.

IMPROVEMENT IN RAILROAD-SWITCHES.

Specification forming part of Letters Patent No. 175,287, dated March 28, 1876; application filed February 16, 1876.

To all whom it may concern:

Be it known that I, CHARLES W. JONES, of the city and county of Philadelphia and State of Pennsylvania, have invented a new and useful Improvement in Safety-Switches; and I do hereby declare the following to be a clear and exact description of the nature thereof, sufficient to enable others skilled in the art to which my invention appertains to fully understand, make, and use the same. reference being had to the accompanying drawings, making part of this specification, in which—

Figures 1 and 2 are plan views of the switch embodying my invention. Fig. 3 is a transverse section in line $x-x$, Fig. 1. Fig. 4 is a transverse section in line $y-y$, Fig. 2; and Fig. 5 is an end view of one of the rails.

Similar letters of reference indicate corresponding parts in the several figures.

My invention consists in the butt end of a switch having the main-track rail overlap the outside rail of the adjacent portion of the main track and the outside rail of the adjacent portion of the side track. It further consists of two guards or guide-plates, extending parallel, and moving with the spring-points, the butt end being jointed to and shifted by the sliding bar of the points, and the opposite end being pivoted to a tie, the guard or plates having each an additional face or sloping flange projecting laterally therefrom.

By these means, one side of the rail is solid and the other is a flange surface, thus allowing the train to pass alternately from either track over a smooth and level surface, the flange surface carrying the wheel from the exposed rail alternately to the main-track rail.

In the event that the switch is wrong for the approaching train, the guards lock the spring-points, respectively, holding firm the point that the switch is set for, and allowing the other point to be moved by the flange of the wheel, the latter point being the only part of the switch that moves when a train passes from the track opposite the one for which the switch is set.

Referring to the drawings, $A A'$ represent the two rails of the main track; $B B'$, the adjacent rails thereof, and $C C'$ the adjacent rails of the side track, the rails $B C$ being at the butt end of the switch. One rail, A , overlaps

the outer rail B of the main track, and the other rail, A' , overlaps the outer rail C' of the side tracks, the rails at the respective laps being firmly bolted and spiked.

It will be seen that the rails $A B$ are continuous, as are also the rails $A' C'$.

$D D'$ represent sliding points, which are arranged between the main rails $A A'$, and they are pivoted at the butt end of the switch to a transversely-sliding bar, E , which will be operated by a switch-lever. The points at the heel end of the switch will be held against the main rails by the actions of springs $F F'$, suitably applied, and which, in the present case, are fitted on the headed rods, which pass loosely through the main rails, and are secured to the points, the springs being confined between the heads of the rods and the adjacent portions of the outer faces of the main rails. To the bar E there are also pivoted two guards, $G G'$, whose opposite ends are pivoted to a tie adjacent to the spring ends of the points $D D'$, and the guards are arranged between the two sliding points $D D'$. From the outer sides of the guards or guide-plates $G G'$ there project flanges $H H'$, which slope in the direction from the butt of the switch to the point thereof. From the outer faces of the sliding points $D D'$, at the butt end of the switch above the bases of the points, there project flanges $J J'$.

It will be seen that the butt ends of the sliding points and guards move together, owing to the action of the bar E .

The operation is as follows: When the parts are in position shown in Fig. 1, the main track is clear for the passage of the train, and the bar E is locked or secured.

It will be seen that the point D and rail B and point D' and rail B' , respectively, are continuous, and the guard G is closely in contact with the point D , thus locking the said point, and preventing the movement of the latter, and insuring the safety of the cars in their passage past the switch.

Should cars run down the side track in the direction of the arrow, when the wheels reach the butt end of the switch, the flange of one wheel—say the right-hand wheel—moves on the flange J' of the point D' , and its head passes over the space a' , occasioned by the overlap-

ping of the rails A' C', until the tread fully reaches the main rail A', when said wheel will run on the said main rail. Then the flange of said wheel enters between the points D' and main rail, thus moving out the former, until the wheel has cleared the point, when the spring F' returns the point to its normal position closed for the main track. The flange of the other wheel—the left-hand wheel in the present case—rides on the sloping flange H of the guard G, and when the tread of the wheel reaches the point D, the said wheel runs on said point, and thus reaches the main track A. It will thus be noticed that the car passed from the exposed ends b b' of the rails C C' to the main track.

In Fig. 2, the switch is shifted from the main track to the side track, and the cars will pass to the side track, as usually. Should, however, the cars be coming on the main rails B B', in the direction of the arrow, the flange of the right-hand wheel will pass from the rail B' onto the flange H' of the guard G', and, consequently, reach the point D' and the main rail A'.

It will be noticed that the point D' is now locked by its adjacent guard G. The flange of the left-hand wheel moves on the flange J of the point D, and its tread passes over the space a, occasioned by the overlapping of the rails A B, until the tread fully reaches the

main rail A, when the wheel will run on said main rail. Then the flange of said wheel enters between the point D and main rail, thus moving the former until the wheel has cleared the point, when the spring F returns the point to its normal position, closed, for the main track. It will thus be seen that the car passed from the exposed ends b'' b''' of the rails B B' to the main track.

Having thus described my invention, what I desire to claim as new, and secure by Letters Patent, is—

1. The switch, having at its butt end the rails of the main track, overlap the outside rail of the adjacent portion of the main track and the outside rails of the adjacent portion of the side track, substantially as and for the purpose set forth.

2. The guards G G', with flanges H H' projecting laterally therefrom, and located adjacent to the sliding points D D', substantially as and for the purpose set forth.

3. The main rails A B, side rails C, movable points D D', sliding bar E, springs F F', guards G G', and flanges H H' J J', constructed, combined, and operating substantially as and for the purpose set forth.

CHAS. W. JONES.
